US00D701610S

(12) **United States Design Patent**
Thomas et al.

(10) **Patent No.:** US D701,610 S
(45) **Date of Patent:** ** Mar. 25, 2014

(54) **REMOTE CONTROLLER FOR PORTABLE TENS DEVICE**

(75) Inventors: **Charles M. Thomas**, Hixson, TN (US); **D. Keith Hagy**, Chattanooga, TN (US); **Donald Kay Riker**, Soddy Daisy, TN (US); **Nathan Anderson Pollock**, Suffolk Park (AU); **Brad Peter Ryan**, Graceville (AU); **Lee Anthony Rodezno**, Rowville (AU); **Troy Christiaan Nyssen**, Flemington (AU)

(73) Assignee: **Modular Therapeutx, LLC**, Soddy Daisy, TN (US)

(**) Term: **14 Years**

(21) Appl. No.: **29/395,406**

(22) Filed: **Jan. 13, 2012**

(51) **LOC (10) Cl.** 14-03

(52) **U.S. Cl.**

USPC **D24/200**

(58) **Field of Classification Search**

USPC D24/169, 186, 200, 209-210; D10/78, D10/81; D13/168; 340/12.22

See application file for complete search history.

(57) **CLAIM**

The ornamental design for a remote controller for a portable TENS device, as shown and described.

DESCRIPTION

FIG. 1 is a top perspective view of the remote controller of our new design.

FIG. 2 is a bottom perspective view of the remote controller of our new design.

FIG. 3 is a front view of the remote controller of our new design.

FIG. 4 is a rear view of the remote controller of our new design.

FIG. 5 is a right side view of the remote controller of our new design.

FIG. 6 is a left side view of the remote controller of our new design.

FIG. 7 is a top view of the remote controller of our new design; and,

FIG. 8 is a bottom view of the remote controller of our new design.

1 Claim, 2 Drawing Sheets
